(57) **CLAIM**

The ornamental design for a shaving razor hanger, as shown and described.

DESCRIPTION

FIG. 1 is a front perspective view of a design of a shaving razor hanger showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is a perspective environmental view thereof.

The portions of the shaving razor hanger shown in broken lines form no part of the claimed design. The other broken lines illustrate environmental subject matter that form no part of the claimed design.

1 Claim, 9 Drawing Sheets
